US0D1085705S

(12) United States Design Patent (10) Patent No.: US D1,085,705 S
(45) Date of Patent:  Jul. 29, 2025

(54) HANDBAG

(71) Applicant: Salvatore Ferragamo S.p.A., Florence (IT)

(72) Inventor: Maximilian Davis, Florence (IT)

(73) Assignee: SALVATORE FERRAGAMO S.P.A., Florence (IT)

() Term: 15 Years

(21) Appl. No.: 35/521,904

(22) Filed: Aug. 7, 2023

(80) Hague Agreement Data

Int. Filing Date: Aug. 7, 2023

Int. Reg. No.: DM/231660

Int. Reg. Date: Aug. 7, 2023

Int. Reg. Pub. Date: Aug. 9, 2024

(30) Foreign Application Priority Data

Feb. 23, 2023 (EM) 015012463-0001
Feb. 23, 2023 (EM) 015012463-0002

(51) LOC (15) Cl. 03-01
